UNITED STATES PATENT OFFICE.

PERCIVAL H. ATKINSON, OF BURNS, OREGON.

LOCK MECHANISM FOR PUBLIC LOCKERS AND THE LIKE.

1,281,266.

Specification of Letters Patent. Patented Oct. 15, 1918.

Application filed June 22, 1917. Serial No. 176,357.

To all whom it may concern:

Be it known that I, PERCIVAL H. ATKINSON, a citizen of the United States, residing at Burns, in the county of Harney, State 5 of Oregon, have invented a new and useful Lock Mechanism for Public Lockers and the like; and I do hereby declare the following to be a full, clear, and exact description of the invention, such as will enable 10 others skilled in the art to which it appertains to make and use the same.

This invention relates to an improved lock mechanism for public lockers of various public places and the like, or for parcel receiving receptacles or compartments and the like, and an object of the invention is to provide a device of this kind, which will dispense with the services of an attendant or the like.

20 A further object of the invention is to provide a simple, efficient and practical device of this kind, having means to be manipulated, by means of a coin or slug (which may be any suitable size desired) for locking said mechanism, thereby releasing a special key or slug, with which the mechanism may be unlocked.

25 A further object of the invention is to provide an improved lock mechanism having a pair of tumblers, so mounted and working on pivots, as to be overbalanced by means of a weight, coin or slug, whereby, when the bolt is thrown into engagement with its keeper, said tumblers will lock the 35 bolt in such position. The tumblers will then grip each other in such manner that the objective end of the lower tumbler will require the weight of a slug, coin or the like, to oscillate the lower tumbler, in order to 40 release or unlock the bolt, and when the lower tumbler is oscillated and both tumblers are at neutral positions, the bolt may be moved from its keeper.

45 A further object of the invention is to provide a pair of chutes or passages for the slugs, coins or special slugs, whereby the tumblers may be actuated, there being means carried by the bolts to cover first one, then the other of the entrances to said passages, 50 to prevent the slugs or coins from being inserted into one or the other of said passages.

55 In practical fields, the details of construction may necessitate alterations falling within the scope of what is claimed.

The invention comprises further features and combinations of parts, as hereinafter set forth, shown in the drawings and claimed.

In the drawings:—

Figure 1 is a view in elevation of the improved lock mechanism for lockers of various public places, for instance, such as bath houses, check rooms and the like.

Fig. 2 is a view in elevation, showing the 65 face plate of the casing of the mechanism removed.

Fig. 3 is a view in elevation of the lock mechanism, showing the face plate of the casing removed and the tumblers of the 70 mechanism in their neutral positions.

Fig. 4 is a view in elevation of the lock mechanism, showing the face plate of the casing broken away in parts and illustrating the tumblers as having been moved 75 to their limits just the opposite to that shown in Fig. 2, and the bolt unlocked and thrown.

Fig. 5 is a sectional view on line 5—5 of Fig. 3.

Fig. 6 is a cross sectional view on line 6—6 of Fig. 3.

Fig. 7 is an enlarged detail view in perspective of the locking bolt.

Referring more especially to the drawings, 85 1 designates a suitable casing, which consists of two sections, a body or receptacle section 2, and a face plate or top section 3, which may be secured to the body or receptacle section by means of suitable screws 90

4. The body or receptacle section is provided with a marginal flange 5, and extending inwardly from the longitudinal portions 5^a of the flange, are auxiliary flanges 6, which have outturned parts 7, thereby 95 forming coin or slug channels 8 and 9, through which coins or slugs may pass.

Mounted in guides 10 formed oppositely to each other in the longitudinal parts 5^a of said flange 5 is a locking bolt 11. Substantially midway the ends of the bolt 11, on one face thereof, a recess 12 is formed. Suitable metallic straps 13 arch over the locking bolt 11, to additionally guide the 100 same, and which straps are secured at 14 to the receptacle section of the casing. On the under surface of the locking bolt 11, adjacent its ends, are notches 15 and 16. A

suitable U-shaped tumbler 17 is provided, and which comprises the side arms 18 and 110

19, the lower terminals of which are provided with laterally bent parts 20 and 21. Projecting upwardly and centrally from the arch 22 of the U-shaped tumbler, is an extension or tongue 23, which is mounted upon the pin 24, thereby pivotally mounting the tumbler, so that it may oscillate in the manner hereinafter set forth. Near the opposite ends of the arch 22 of the U-shaped tumbler, 5 upwardly projecting lugs 25 and 26 are provided, adapted to alternately engage the notches 15 and 16 of the bolt 11, in the manner hereinafter set forth. The auxiliary flanges 6 are provided with cut away portions or openings 27 and 28, which will alternately receive the laterally bent portions 20 and 21 of the arms 18 and 19 of the tumbler 17. Pivotally mounted upon a pin 29, which projects from the inner face of the 10 back wall of the receptacle section is a tumbler or oscillatory member 30, which is provided with downwardly curved ends or portions 31, which play between the auxiliary flanges 6 and the face plate section 3 of the casing. In order that the curved portions 15 31 may play in the channels or passages 8 and 9, the outwardly bent parts or flanges 7 are cut away, as shown at 32 and 33. The lower part of the receptacle section of the 20 casing, as shown at 34, is designed to receive the coins, which are used to operate the mechanism. One of the flanges 6, below the cutaway portion 28, is provided with an additional cutaway part 35. A partition 36 25 rises upwardly from the lower part of the marginal flange 5 of the receptacle casing, thereby dividing off a compartment 37 for the slug *b* that enters the channel or passage 9, and which slug may be removed from the 30 compartment through the opening 38 of the face plate section of the casing. The face plate section of the casing is provided with an opening 39, which, as shown, is covered by a closure 40, which may be locked in any 35 suitable manner. By unlocking the closure 40, the coin deposits may be removed from the compartment or magazine 34. Secured at 41 to the locking bolt 11, is a bar 42. The upper part of the bar 42 inclines upwardly 40 to one side and terminates in a horizontal portion 43 having a bent part 44, which, when the locking bolt is in locked position, covers the entrance opening to the coin passage or channel 8, thereby preventing a coin 45 from passing into said channel. The lower part of the bar 42, at its lower end, has a lateral portion 45, which is provided with an outwardly turned tongue or lug 46, which plays in the cutaway part 35 of one of the 50 flanges 6. The extension or tongue 23 extends through the recess 12. A rocking member 47 has its shank 48 mounted in suitable bearings of the receptacle and face plate sections of the casing. The inner end of the shank 55 48 of said rocking member 47 has a lateral

extension 49, over which a metallic strap 50 arches to guide the extension or part 49 as the member 47 and its shank are rocked. The end part 51 of the extension 49 engages the notch 52 of the locking bolt 11.

On the outer face section 3 of the casing is a suitable key or slug entrance controlling mechanism 53 of any conventional construction. An example of this mechanism 53 can be found in the application of P. H. Atkinson, filed September 27, 1916, Serial Number 122,458, therefore, so far as the operation and the structure of this mechanism is concerned, it is immaterial and entirely unnecessary to enter into a lengthy disclosure of the same in the present case. However, it might be said that the mechanism of the aforesaid co-pending application is designed mainly to provide an entrance controlled mechanism, whereby the entrance opening 54 may receive a specially designed slug, whereby the present lock mechanism may be operated for a predetermined period, so as to limit the rental or the use of the locker, and which entrance opening may be altered in shape to receive varied shapes of slugs.

In using this mechanism, the door of the locker is normally unlocked, preferably open. The person to use the locker may drop a coin through the channel or passage 8 at its upper end. However, the entrance opening to the passage 8 may be provided with a mechanism similar to 53, and in this case the person to use the locker may buy or purchase a special slug, which may be passed through the channel or passage 8. In either case, however, the coin, slug or weight, as indicated at *a*, contacts with one of the curved parts 31 of the oscillatory tumbler 30, thereby moving the same to a substantially neutral position, as shown in Fig. 3, until the terminal of the curved portion 31 (which is so engaged by the coin or slug) contacts with the lateral portion 20 of the arm 18 of the U-shaped tumbler 17, thereby overbalancing the tumbler 17 to its neutral position, as shown at 23. When these parts are so operated, the coin *a* is supported, as shown in Fig. 3. The operator then rocks the member 47, causing the extension 49 to throw the bolt 11 to a locked position, as illustrated in Fig. 4. When the bolt is moved to this position, the coin further overbalances the tumbler 30, allowing the coin to drop into the compartment 34, and owing to the extremity 55 of the curved portion 31 having been in engagement with the lateral part 20, the tumbler 17 is tilted from its neutral position in Fig. 3 to the position shown in Fig. 4, until the lug 26 engages the notch 16, thereby holding the bolt in its locked position. When the bolt is moved to the position shown in Fig. 4, the lateral lug 46 (which supports the slug or weight *b*, as shown in Fig. 3) is moved from the path 130

of the slug *b*, releasing the same and allowing it to fall into the compartment 37, where it may be removed by the person or operator who in the first instance purchased or 5 rented the locker. When the operator or person renting the locker desires to open the same after finishing bathing or for removal of that which is being temporarily stored therein, deposits the slug *b* in the passage 10 9 through the entrance opening 54. The slug will then contact with the curved portion 31 at the right hand end of the tumbler 30 and cause the tumbler 30 to become overbalanced until its extremity 56 will contact 15 with the lateral lug 21 of the arm 19 of the tumbler 17, in a manner similar to the engagement of the extremity 55 with the lateral part 20. Just so soon as this is accomplished the tumbler 17 becomes overbalanced 20 until its lug 25 engages the notch 15, that is when the bolt 11 has been moved to the position shown in Fig. 2, in which case, the various tumblers will assume the positions shown in Fig. 2, with the bolt locked in an un- 25 locked position in readiness to be unlocked by a coin of another person purchasing the locker.

The invention having been set forth, what is claimed as new and useful is:—

30 1. In a lock mechanism for public lockers, a casing, a sliding bolt mounted in guides of said casing, means to extend and recede said bolt, and pivoted means to be weighted first on one side and then the other 35 to lock the bolt in an extended position and then in a receded position, said casing having a pair of passages, through either one of which a weight may pass to engage said pivoted means, said passages having weight 40 receiving mouths, a member carried by said bolt and adapted to partially cover one of said mouths and a controlling mechanism for the other mouth.

45 2. In a weight actuated lock mechanism, a casing, a bolt slidably mounted therein and provided with a pair of notches, means to move the bolt to an extended or receded position, and a pivoted tumbler to be actuated by a weight and provided with a pair of 50 lugs to coöperate and engage with first one and then the other of said notches to lock the bolt in an extended or receded position.

55 3. In a weight actuated lock mechanism, a casing, a bolt slidably mounted therein and provided with a pair of notches, a pivoted tumbler having a pair of lugs and adapted to be actuated by a weight, whereby said lugs may engage first one and then the other

of said notches to lock the bolt in an extended or receded position. 60

4. In a weight actuated lock mechanism, a casing, a bolt slidably mounted therein and provided with a pair of notches, a pivoted tumbler having a pair of lugs and adapted to be actuated by a weight, whereby said lugs may engage first one and then the other of said notches to lock the bolt in an extended or receded position, said casing having a pair of passages through either one of which a weight member may pass, said 70 tumbler having a pair of lugs each to extend across the path of the lower end of one of said passages to be engaged by said weight for actuating the tumbler.

5. In a weight actuated lock mechanism, a 75 casing, a bolt slidably mounted therein and provided with a pair of notches, a pivoted tumbler having a pair of lugs and adapted to be actuated by a weight, whereby said lugs may engage first one end and then the other of said notches to lock the bolt in an extended or receded position, said casing having a pair of passages through either one of which a weight member may pass, said 80 tumbler having a pair of lugs, each to extend across the path of the lower end of one of said passages to be engaged by said weight for actuating the tumbler, said passages having entrance openings at their upper ends through which the weight may be 85 passed into the passages, and a member carried by the bolt to cover one of said openings, and a controlling mechanism for the other opening.

6. In a weight actuated lock mechanism, 95 a casing, a bolt slidably mounted therein and provided with a pair of notches, a pivoted tumbler having a pair of lugs and adapted to be actuated by a weight, whereby said lugs may engage first one and then the 100 other of said notches to lock the bolt in an extended or receded position, said casing having a pair of passages through either one of which a weight member may pass to actuate said tumbler, said passages having 105 entrance openings at their upper ends for the weight member, and a member carried by the bolt to cover one of said entrance openings.

In testimony whereof I have signed my 110 name to this specification in the presence of two subscribing witnesses.

PERCIVAL H. ATKINSON.
